(57) **CLAIM**

I claim the ornamental design for a drawer for refrigerator, as shown and described.

DESCRIPTION

FIG. 1 is a top perspective view of a drawer for refrigerator of the present invention;

FIG. 2 is a front view thereof;

FIG. 3 is a top view thereof;

FIG. 4 is a rear view thereof; and,

FIG. 5 is a first side view thereof, the second side view being a mirror image thereof.

The broken lines shown represent unclaimed subject matter and form no part of the claimed design.
